UNITED STATES PATENT OFFICE.

JOHN REID, OF LONDON, ENGLAND.

FURNACE.

Application filed January 30, 1923. Serial No. 615,897.

To all whom it may concern:

Be it known that I, JOHN REID, a subject of the King of Great Britain and Ireland, residing at London, England, have invented

5 **Improvements in or Relating to Furnaces,** of which the following is a specification.

In the combustion of fuel on the grate of a steam boiler furnace it is found, with natural draft, that, owing to insufficient air, combustion is very sluggish at some parts of the grate, more especially the front part, and at other parts of the grate, especially towards the back and in places where holes or thin patches occur in the fuel bed, an 10 amount of air passes through the grate in excess of that required for effective combustion. Similar conditions obtain with forced draft and, though forced draft enables a higher general rate of combustion to be obtained with the same height of chimney or 15 funnel, the amount of air driven through the grate exceeds that required for combustion.

The object of the present invention is to 20 provide means for directing air to the front part of the grate which can be readily fitted in existing furnaces provided with hollow forced draft fronts. The said means comprise a casting with longitudinal division 25 plates and floor plate and adapted to be bolted into an existing hollow furnace front so as to extend across the said front and through the ashpit opening in the back thereof and under the furnace dead plate, 30 the arrangement being such that air fed by a fan or equivalent through valves into the furnace front in the usual way is largely caught by the said means and directed thereby through the front part of the furnace 35 grate, while the remainder of the grate receives air from the ash-pit, these supplies of air giving an adequate and approximately correct amount of air for proper combustion; the air passing to the grate through 40 the ashpit may be supplied by the fan or equivalent, or may be admitted thereto from the stokehold, the chimney or funnel draft being sufficient to draw the air through the 45 grate.

50 The accompanying drawings show an ordinary type of boiler furnace adapted for carrying out the invention, Fig. 1 being a longitudinal section and Fig. 2 a cross section through the furnace front illustrating 55 one arrangement. Figs. 3 and 4 are frag-

mentary views similar to Figs. 1 and 2 of a modified arrangement.

The furnace tube *a* is fitted with a grate *b*, dead plate *c*, bridge *d*, and a hollow forced draft furnace front *e* as usual; the front shown has top and side air valves and an air cooled baffle around the firing opening as well understood.

In order to direct air through the front part of the grate there is bolted to the back plate *e* of the front a casting *f* which projects horizontally beneath the dead plate *c* through the upper part of the ashpit opening of the front and which has depending therefrom a number of longitudinal division plates *f*¹, *f*² forming channels which are closed at the bottom by a floor plate *g* which extends to the front plate *e*² of the front; the centre division plate *f*¹ extending nearly to the said front plate and the plates *f*² on each side thereof to successively less distances so that fan air flowing through the valves of the front reaches the several channels in adequate quantity and is directed without material loss of velocity directly to the front end of the grate. The floor plate may be extended beneath the grate by an attached upwardly curved portion *g*¹ as shown. The pressure of the air is less than that usually employed and to enable the pressure to be kept low, air heaters in the uptakes are dispensed with or so constructed as to offer little obstruction. In practice, the fan is run so that the funnel can maintain a partial vacuum at the foot of the uptake. The floor plate *g* may thus extend from side to side within the hollow front so as to cut off the fan draft air from the lower part, through which air will flow from the stokehold into the ashpit, the usual door being removed. By shutting off the fan the furnace can be worked under natural draft, while by omitting or by removing side portions of the casting with attached division plates and floor plate or otherwise providing for the passage of some air from the fan to the ashpit and fitting an ashpit door, the furnace can be worked entirely with fan air at comparatively low pressure or under forced draft.

In some places the dead plate *c* and the top casting *f* may be slotted or perforated so as to cause energetic combustion of the fuel close up to the furnace front, and, in new work it is preferred to shorten the cast-

ing f and fit a steeply sloping slotted dead plate and lower the front end of the grate, thereby ensuring that a good supply of fan air is delivered into the extreme front end 5 portion of the fuel bed.

At the back end of the ashpit a suitably curved air directing plate h is fitted against the bridge support so as to smoothly direct air towards the grate.

10 As a further modification the arrangement shown in Figs. 3 and 4 may be adopted where the bottom or floor plate g^1 is movable about a hinge i^1 . The lower edges of the division plates f^{11}, f^{22} in this case 15 are not straight but shaped somewhat as shown so that the plate g^1 , which normally occupies the position illustrated in Fig. 3, may be lifted at the front edge about the hinge, thereby giving more clearance when 20 clearing out ashes and held in such position to vary the proportion of air passing up through the front part of the grate. j are plate members carried by the plate g^1 and arranged closely adjacent to the channel 25 walls of the casting f^a to normally complete such channels and still allow the plate g^1 to be tilted.

What I claim is:

30 1. In a steam boiler furnace having a hollow front, grate and ash-pit, an air directing device comprising a casting with longitudinal division plates and a floor plate adjustable with respect to said casting and removably secured in said hollow front so as to extend inwardly from the front thereof into and partially through the ash-pit opening in the back thereof, thus dividing the space between the grate 35 and the bottom of the ash-pit, substantially 40 as described.

2. In a steam boiler furnace having a hollow front, grate and ash-pit, an air directing device comprising a casting with longitudinal division plates of different 45 lengths and an independently adjustable floor plate adapted to be removably secured in said hollow front so as to extend inwardly from the front thereof into and partially through the ash-pit opening in the 50 back thereof, said floor plate being provided with an arcuate extension and divid-

ing the space between the grate and the bottom of the ash-pit, substantially as described.

3. In a steam boiler furnace having a 55 hollow front, grate and ash-pit, an air directing device comprising a casting with longitudinal division plates, an independently adjustable floor plate removably secured in said hollow front, said casting and 60 plate extending inwardly into the space between the grate and the bottom of the ash-pit, and an apertured dead plate arranged above the floor plate, substantially as described. 65

4. In a steam boiler furnace, the combination of a hollow furnace front, grate and ash-pit and an air directing device comprising a top plate extending from the back plate of the hollow front into the ashpit of the furnace, an adjustable subjacent floor plate, removably secured in said hollow front and extending forwardly across the furnace front and backwardly through the ash-pit 70 opening in said back plate, and longitudinal 75 division plates between said top and floor plates extending into the hollow furnace front, the spaces between the longitudinal division plates being open at the top within the area of the furnace front, substantially as described. 80

5. In a steam boiler furnace, the combination of a hollow furnace front, grate and ash-pit and an air directing device comprising a top plate extending from the back plate of the hollow front into the ash-pit of the furnace, an adjustable subjacent floor plate removably secured in said hollow front and extending forwardly across the furnace front and backwardly through the ash-pit opening in said back plate and beyond the top plate, and longitudinal division plates between said top and floor plates extending into the hollow furnace front, the spaces between the longitudinal division plates being open at the top within the area of the furnace front, substantially as described. 85 90 95

Signed at London, England, this 11th day of January, 1923.

JOHN REID
